UNITED STATES PATENT OFFICE.

WATSON WILLIAM McKEE, OF TACOMA, WASHINGTON.

COMBINATION SHIPPING AND SHOW CASE.

SPECIFICATION forming part of Letters Patent No. 784,751, dated March 14, 1905.

Application filed April 28, 1904. Serial No. 205,326.

To all whom it may concern:

Be it known that I, WATSON WILLIAM McKEE, a citizen of the United States, residing at Tacoma, Washington, have invented a new 5 and useful combination shipping and show case for the packing, shipping, and displaying of goods, more particularly cakes, cookies, crackers, and confectionery, of which the following is a specification.

10 This invention relates to improvements in combination packing, shipping, and show cases.

The object of the invention is to provide a case of this character in which goods may be packed 15 and shipped and which may be readily converted into a show-case for displaying the goods contained therein.

A further object is to provide a combined packing, shipping, and display case which 20 will be simple, strong, durable, and inexpensive in construction and which will be particularly adapted to contain cakes, crackers, or confectionery.

With these and other objects in view the 25 invention consists of certain novel features of construction, combination, and arrangement of parts, as will be hereinafter more fully described, and particularly pointed out in the appended claims.

30 In the accompanying drawings, Figure 1 is a perspective view of the box forming part of the case, the cover of the box being shown in raised position. Fig. 2 is a rear perspective view of the frame, which is adapted to be 35 removably connected to the front of the box to support the transparent view-plate. Fig. 3 is a vertical sectional view through the front of the box, the frame connected thereto, and the transparent plate supported by said frame; 40 and Fig. 4 is a fragmentary horizontal sectional view through one corner of the box and frame, showing the manner of connecting the latter to the box.

Referring more particularly to the drawings, 45 1 denotes a box or receptacle which is preferably, though not necessarily, rectangular in shape and which may be formed of any suitable material, but is preferably constructed of paper.

50 The box 1 consists of front and rear walls

2 and 3, side walls 4, a bottom 5, and top 6, formed from a single piece of strong stiff paper so cut and bent or folded as to form a box. On the side edges of the rear wall 3 is formed angularly-bent flanges 7, which are adapted to 55 overlap and to be joined to the side walls 4 of the box by gluing, riveting, or other suitable form of connection. The side edges of the front wall 2 have also formed thereon angularly-bent flanges 8, which are riveted, glued, or 60 otherwise secured to the front edges of the side walls of the box, as shown at 9. The flanges 8 are provided with extensions 10, which project beyond the riveted or glued portion of the same. The purpose of said extensions will be hereinafter described. The top 6 is adapted to fold over and close the upper end of the box and is provided on its free edges with angularly-bent flanges 12, 65 which are adapted to engage the upper walls 70 of the sides and front of the box to form a tight closure for the same.

The front wall of the box is provided with a square or other shaped outline of perforations 13 to permit the portion of the wall 75 enclosed by said perforations to be readily torn out, thereby forming a view-opening through which the contents of the box may be seen. Over said opening and connected to the front wall is arranged a metallic frame 14, consisting of a plate 15, in which is formed an opening 16, preferably corresponding in size and shape to the opening formed by the removal of the perforated portion of the front wall. The side edges of the plate 15 are bent to form 80 right-angular rearwardly-projecting flanges 17, the outer edges of which are bent or folded back upon themselves to form hook-shaped members 18, which are adapted to be engaged with the free edges or extensions 10 of the 85 flanges 8 on the front wall of the box. Said extensions 10 are cut in, as at 19, to receive hook members 18, which are pinched or pressed together at their upper ends to engage the edge of the extensions where the same are cut 90 in, and thereby support the frame in place on the front of the box. The upper edge of the plate 15 is turned upon itself to form a bead 20, which finishes off said upper edge. The lower edge of the plate 15 is bent inwardly to 95 100

form a curved flange 21, which is adapted to support a plate 22, of glass or other suitable transparent material, which is slipped into the frame 14 behind the plate 15 and between the flanges 17, as shown. The plate 22 is held in position near its upper edge by a cross-bar 23, having right-angular offset ends by which it is attached to the rear side of the plate 15 near the upper edge of the same. The transparent plate 22 prevents the contents of the box from falling out through the view-openings in the front wall and frame of the case and at the same time permits the contents of the box to be observed.

15 The frame 14 and transparent plate 22 may be attached to the box after the same is packed and may be shipped therewith or the frames and boxes may be shipped separately and the frames retained by the storekeeper who may 20 arrange the same in place on the box after tearing out the perforated portion in the front wall of the same.

If desired, the perforated portion of the front wall of the box may be left intact and 25 samples of the contents of the box placed in the frame 14 between the front wall of the box and the transparent plate 22 of the frame, thus displaying the goods through the opening 16 in the front plate 15 of the frame.

30 The lower curved flange 21 of the front plate of the frame serves to space said plate from the front wall of the frame and also to form a bottom for said space to support the goods which may be placed therein, the goods 35 being retained in place at the upper end of the space by the cross-bar 23, the flange 21 and cross-bar 23 therefore serving the double purpose of holding the transparent plate and also the display-samples of the goods.

40 By the construction and arrangement of a box as herein shown a strong, light, and inexpensive packing, shipping, and display case is provided which will serve all the purposes of a heavy expensive box for holding goods 45 of the character described.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of 5 this invention.

Having described my invention, what I claim as new, and desire to secure by Letters Patent, is—

1. A box having a front formed with side flanges secured on and partially overlapping the opposite sides thereof, and a frame having an opening and provided with sides which are

provided with flanges to engage those of the box and detachably secure the said frame to the said box, for the purpose set forth, substantially as described.

2. A packing, shipping and displaying case, consisting of a box formed by side, front and rear walls, a bottom connected to said walls, a top adapted to fit over and close the upper end of said box, flanges formed on the edges of the front and rear walls whereby the same are connected to said side walls, means whereby a portion of the front wall may be readily removed to form a view-opening, a vertically-disposed transparent panel or plate arranged over the front of said box to cover said opening and means whereby said plate is held in place and supported in a vertical position, substantially as described.

3. A packing, shipping and displaying case consisting of a box formed by side, front and rear walls, a bottom connected to said walls, a flanged top adapted to fit over and close the upper end of said box, flanges formed on the edges of said front and rear walls whereby the same are connected to said side walls, extensions formed on the flanges of said front wall, a transparent panel or plate arranged over the front wall of said box, and spaced from the same, means whereby said plate is supported upon and spaced from said front wall, said supporting and spacing device also forming closures for said space, substantially as described.

4. A packing, shipping and displaying case consisting of a box formed by side, front and rear walls, a bottom connected to said walls, a flanged top adapted to fit over and close the upper end of said box, flanges formed on the edges of said front and rear walls whereby the same are connected to said side walls, extensions formed on the flanges of said front wall, an open frame arranged on the front of said box, hook-shaped side flanges formed on said frame, said flanges being adapted to be removably engaged with the extensions formed on the flanges of the front wall thereby removably securing said frame in place, an inwardly-projecting curved flange formed on the lower end of said frame, a transparent plate arranged in said frame, and supported by said curved flange, and a cross-bar arranged near the upper end of the frame to hold said plate in place and to close the upper end of the space between said plate and the front of the box, substantially as described.

In testimony whereof I have signed my name to the specification in the presence of two witnesses.

WATSON WILLIAM MCKEE.
